UNITED STATES PATENT OFFICE.

JOHN FLISEK, OF STEUBENVILLE, OHIO.

BOAT DRIVE AND CONTROL.

1,360,105.

Specification of Letters Patent. Patented Nov. 23, 1920.

Application filed September 16, 1920. Serial No. 410,668.

To all whom it may concern:

Be it known that I, JOHN FLISEK, citizen of Poland, residing at Steubenville, in the county of Jefferson and State of Ohio, have 5 invented certain new and useful Improvements in Boat Drives and Controls, of which the following is a specification.

This invention relates to boats, having more particular reference to small boats 10 adapted for manual propulsion.

The invention has for an object to provide a novel arrangement of steering and propelling mechanism adapted to permit of the boat being either steered or propelled 15 as desired by a single manually operable element.

For further comprehension of the invention, and of the objects and advantages 20 thereof, reference will be had to the following description and accompanying drawings, and to the appended claims in which the various novel features of the invention are more particularly set forth.

Figure 1 of the drawings is a plan view 25 of a boat having the invention applied thereto.

Fig. 2 is a longitudinal vertical section through the median line of the boat.

Fig. 3 is an enlarged fragmentary longitudinal sectional view on the same line as 30 Fig. 2.

The hull of the boat is indicated at 10 and 35 may be of any approved construction, the usual rudder being shown at 11. The boat is adapted to be propelled by a screw propeller 12 of ordinary type which is fixed on the rear end of a shaft 13 extending longitudinally through the boat just above the 40 keel thereof, and supported in suitable bearings, this propeller being adapted for manual operation.

To this end the forward end of shaft 13 has fixed thereon a bevel gear 14 which 45 meshes with a like gear 15 on the lower end of a shaft 16 extending vertically in the boat near the bow thereof, this shaft being supported by suitable bearings such as 17.

* The upper end of this shaft 16 has fixed 50 thereon a second bevel gear 18 which meshes with a like gear 19 on a short horizontal shaft 20 which extends longitudinally of the boat and may be supported by suitable bearings such as 21.

Upon this shaft 20, is loosely mounted a 55 toothed crank wheel 23 which is adapted to

have longitudinal movement therealong to bring it into or out of driving relation with the shaft, this crank wheel having a handle 24 thereon for turning purposes. To effect the above mentioned operative engagement 60 or disengagement of the crank wheel with the shaft 20 the latter is provided with a comparatively short spirally disposed groove 25 which communicates at its rear end with a circumferential groove 26, a screw 27 on 65 the hub of the wheel projecting into either of these grooves according to the location of the wheel on the shaft.

When the wheel 23 is pulled backward on the shaft 20 until the screw 27 engages in 70 the circumferential groove 26 the wheel may rotate independently of the shaft, but when the wheel is pushed forward on the shaft 20, moving the screw 27 into the spiral groove 25, rotation of the wheel 23 by the 75 handle 24 in the proper direction will cause the shaft 20 to rotate and the propeller 12 to be driven by the connecting mechanism above described. If rotation of wheel 23 is stopped the continued rotation of shaft 80 20, due to the momentum of the boat will throw the wheel backward, the screw 27 moving through the spiral groove 25 until it reaches the circumferential groove 26.

I preferably arrange the control mechanism 85 of the rudder in such a manner that this backward movement of the wheel 23 will bring it into operative relation therewith. This control mechanism comprises a rope 30 connected at opposite ends to arms 90 on the rudder post and led forward around suitable guide pulleys 31, being also led around and fastened to a pair of steering pulleys 32 fixed on vertical shafts 33 arranged adjacent opposite sides of the boat 95 and supported by suitable bearing brackets 34, these pulleys having handles 35 fixed thereon.

The means by which the wheel 23 is connected with the steering mechanism comprises a pulley 36 on each of the vertical 100 shafts connected by belts 37 with a double grooved pulley 38 fixed co-axially to a gear 39, this gear and pulley being mounted on a suitably supported stub shaft 40 located 105 below the shaft, the gear being positioned to be engaged by the gear teeth on the crank wheel 23 when the latter is moved rearwardly to the position free to rotate on the shaft, the teeth on the crank wheel dis- 110

engaging from the gear 39 when the former is moved forward to driving relation with the shaft 20.

It is believed the manner of operation 5 of my improved steering and driving mechanism will be apparent from the above description. When the wheel 23 is moved forward it engages the shaft 20 but is disengaged from the steering mechanism but 10 when it is moved backward it engages the steering mechanism, thus providing for the more easy control of the boat during times, such as when a landing is being effected, requiring special attention to the handling 15 of the boat. The boat may be provided with suitable seats 42.

Having thus described my invention what I claim as new and desire to protect by Letters Patent of the United States is as 20 follows:

1. In a boat propelling means including a shaft, a manually rotatable wheel loose on said shaft, said shaft having a circumferential groove and a communicating spiral groove formed therein, and a part carried by said wheel adapted to be engaged in either of said grooves by moving said wheel along said shaft.

2. In a boat propelling means including

a shaft, a manually rotatable wheel loose on 30 said shaft, said shaft having a circumferential groove and a communicating spiral groove formed therein, and a part carried by said wheel adapted to be engaged in either of said grooves by moving said wheel 35 along said shaft, and steering means including a gear operatively engaged by said wheel when the said part is engaging in the said circumferential groove.

3. In a boat propelling means including 40 a shaft, a manually rotatable wheel loose on said shaft, said shaft having a circumferential groove and a communicating spiral groove formed therein, and a part carried by said wheel adapted to be engaged in 45 either of said grooves by moving said wheel along said shaft, said steering means including a pair of vertically arranged shafts, a pulley on each of said shafts, a gear adapted to be engaged with or disengaged 50 from said crank wheel as the latter is moved along the first mentioned shaft, a pair of pulley elements fixed co-axially to said gear, and belts connecting said pulley elements to said first mentioned pulleys. 55

In testimony whereof I have affixed my signature.

JOHN FLISEK.
